UNITED STATES PATENT OFFICE.

NATHAN C. HEATON, OF WESTMONT, ILLINOIS, ASSIGNOR TO MONTGOMERY WARD & COMPANY, OF CHICAGO, ILLINOIS, A CORPORATION OF ILLINOIS.

FEED MECHANISM FOR STENCIL-CUTTING MACHINES.

Application filed December 23, 1924. Serial No. 757,676.

The invention relates to stencil cutting attachments for typewriting machines, such as covered by my pending application for patent filed October 20, 1923, Serial No. 669,650, the improvements herein shown and described being directed to novel mechanism for feeding the cards or other form of records to the typewriting machine and delivering the same from the latter after the printing and stenciling operations have been completed.

In the use of the attachment of my former application the feed of the record cards to the platen is effected by direct manual application of the individual cards. The moistening of the stencil sheets of the cards also must be effected manually. By reason of this necessary manual effort the operation of the attachment in question is relatively slow, and the output of the machine with which the attachment is employed is restricted in volume.

The invention herein disclosed has for its main and primary object the provision of feed mechanism by which the introduction of the record cards to the typewriting machine is effected automatically and in regular sequence, and by which the stencilled cards, or other forms, are automatically discharged after the printing and stencilling of the same have been completed.

The invention further aims to provide feed mechanism of the character mentioned having provision for automatically moistening the stencil sheets in advance of the cutting operation thereon, so that when presented to the action of the type for the stencilling operation the sheets will have become properly conditioned therefor.

A further object of the invention is to provide feed mechanism such as described which is combined and coordinated with the typewriting machine in such manner as to utilize the usual movements of the operator, expended in the positioning of the writing head with respect to the platen for writing purposes, for actuating the feed mechanism.

The introduction, therefore, of the record cards and their removal from the machine after having been typed and stencilled, are incident to the usual operation and positioning of the writing head for writing purposes, and excess effort by the operator for actuating the feed mechanism thereby is avoided. This conduces to conservation of

the energy of the operator with a resultant increased output of the typewriting machine.

Other objects and advantages will appear as the nature of the improvements is better understood, the invention consisting substantially in the novel construction, combination and arrangement of parts hereinafter fully described, illustrated in the accompanying drawings, and pointed out in the appended claims.

While the form of the invention herein shown and described presents a practical embodiment thereof, it will be understood that the same is merely illustrative of one application of the inventive concept, and is not to be limited thereto, so that the present disclosure is not to be taken in a restrictive sense.

In the drawings:

Fig. 1 is a top plan view of a feed mechanism embodying the herein-described invention and illustrated in its application to a flat platen typewriting machine;

Fig. 2 is a longitudinal sectional view on the line 2—2, Fig. 1;

Fig. 3 is a transverse sectional view on the line 3—3, Fig. 1;

Fig. 4 is a similar view on the line 4—4, Fig. 1;

Fig. 5 is a detail sectional view on the line 5—5, Fig. 1;

Fig. 6 is a similar view of the moistening pad and an associated record card illustrating the relative positions of these elements during the moistening operation;

Fig. 7 is a transverse sectional view on the line 7—7, Fig. 2;

Fig. 8 is a detail sectional view, on an enlarged scale, of the card-stopping mechanism for positioning the cards on the platen of the machine;

Fig. 9 is a similar view on the line 9—9, Fig. 8; and

Fig. 10 is a face elevation of a record card in the printing and stencilling of which the present invention has special application.

Having reference now in detail to the accompanying drawings, the numeral 10 designates the writing head of a flat platen typewriting machine. This is one of the general type now commonly employed for book or flat platen work, and the present invention is not concerned with the machine itself as such. The head 10 has the usual mounting for transverse movement on a car-

riage 11, and this carriage is slidably mounted for reciprocatory movement on a pair of guide rails 12, which rails constitute a part of the general framework of the machine. 5 There is included in this general framework a platen 13, which constitutes a part of the subject-matter of the invention covered by my former application Serial No. 669,650, filed October 20, 1923, now Patent 1,660,008 10 issued Feb. 21, 1928, and reference is made to that particular application for a more complete disclosure of the construction and utility of this platen.

The numeral 14 designates the shift bar 15 of the line spacing mechanism having an operating handle 15; 16 designates a stop block with its contact head 17, and 18 a stop dog in its mounting block 19 for co-operation with the stop block 16. As specified in the former application referred to, the utility of the stop block 16 is for limiting and positioning the carriage 11 of the writing head 10 so as to properly relate the same to the record card operated upon 25 when the card is positioned over the platen 13. Such a card is illustrated in Fig. 10, the numeral 20 designating the body of the card, 21 the space in which the name of the customer is usually printed at the head 30 of the card, and 22 the usual fibrous material which is employed as the stencil sheet. In this sheet the name and address of the customer is stencilled or cut so that the stencil sheet may be employed in addressing 35 communications to the customer, and in other uses where the name and address of the customer are to be imprinted.

The parts above described indicate the general relation of the cutting attachment 40 of the former application to a platen typewriting machine, and the present invention contemplates an association therewith of novel and efficient means for feeding the cards to the platen 13, without the application 45 of direct manual effort thereon in such feeding operation, the cards being automatically fed during the operation of the writing head in the usual movements thereof by the operator, and discharged from the machine 50 after the printing operation and also the cutting of the stencil sheet of the individual cards. To the attainment of this end the guide members 23 of the platen 13 are elongated, and extend substantially throughout 55 the length of the frame of the typewriting machine. They are suitably supported by the framework of the machine, and thus bear a fixed relation thereto and to the operation of the carriage of the machine as the 60 latter is moved in relation to the framework.

At the rear end portions of the guide members 23 is located a magazine for the record cards. This is formed of four vertically disposed angle members 24, two of said members being mounted at their base portions

upon the guide members 23 by a supporting angle member 25. These angle members are separated sufficiently to accommodate the cards 20, the corners of which are guided by the vertically disposed angle members 24, 70 and the latter, in their combined relation, constitute an open chute wherein the cards are disposed in superimposed relation and discharged at the bottom of the chute in regular succession.

The guide members 23 are grooved at their inner faces as at 26, as in the construction covered by the previously identified application, the grooves 26 constituting guide channels along which the cards are 8 adapted to move from the rear ends to the forward ends of the members 23. These channels are in communication with the lower end of the card magazine in order to receive the cards as they leave the magazine, 9 the grooves 26 supporting the cards in their transit from the magazine to the platen 13.

A feed plate 27 is slidably mounted in additional grooves 28, also formed at the inner faces of the rear ends of the guide members 23, and said grooves 28 are in a lower plane than the grooves 26. This permits the thickness of at least one card to intervene between the surface of the plate 27 and the lower ends of the magazine members 24, thus enabling the lowermost card readily to clear the lower end of the magazine and to be projected forwardly therefrom into the guide channels 26. Such movement of the lowermost card is induced by the forward movement of the feed plate 27, an engaging dog 29 being pivotally mounted at the underside of the plate 27 and projecting upwardly through a slot therein for engagement with the lowermost card of the stack. A spring 30 urges the dog 29 normally upwardly and into engaging relation with the lowermost card. Obviously, the yielding mounting of the dog 29 will permit the same readily to be depressed as the plate 27 is retracted, thus permitting the dog to ride over the next lowermost card of the stack for engagement with the rear edge thereof after the plate 27 has been moved back to its rearmost position.

The movement of the plate 27 is effected by a lever 31 pivotally connected, as at 32, to the framework of the machine, and said lever 31 has a pin and slot connection 33 with the plate 27. Thus, as the lever 31 is rocked upon its pivotal point 32 the plate 27 will be moved backwardly and forwardly. A link 34 is connected to the lever 31, which link, in turn, is connected to an operating slide 35 which is supported in the framework of the machine and adapted for reciprocatory movement lengthwise of that framework. When the slide 35 is pushed rearwardly, in a manner to be later explained, the forward movement of the feed plate 27

is effected for discharging the lowermost card from the magazine, and upon appropriate conditions arising, as will appear later, a spring 36 exerts its pull to retract the feed plate 27. This spring is connected to the lever 31 at its end to which the link 34 is connected, and is also anchored on the framework of the machine, the points of connection of the spring with the lever 10 and the framework being designated by the numerals 37 and 38. In the action of the spring 36, when retracting the plate 27, the operating slide 35 also is moved towards the forward end of the machine and restored to its normal position, or that which it occupies for effecting discharge of the lowermost card of the stack in the magazine.

The operating slide 35 is actuated on its rearward or feeding movement by the carriage 11 as the latter is moved rearwardly on the rails 12 to position the writing head in relation to the card 20 on the platen 13 for writing the name of the customer in the space 21 thereof. This is the position of the carriage 11 and the writing head 10 which is illustrated in Fig. 1, in which position and at which time the forward member of the frame 11 is in abutting relation with the stop block 16, or to the limit of the rearward movement of that frame. Operating engagement of the carriage 11 with the slide 35 is effected by means of an escapement dog 39, which is pivotally mounted on the machine frame 11, as at 40, which escapement 35 dog coacts with a latching dog 41 pivotally connected, as at 42, to the lower side of the slide 35. This dog extends upwardly through a slot 43 in the slide 35, and is urged normally upwardly by a spring 44. The escapement dog 39 has a coil spring 45 connected thereto, which spring is anchored to the carriage 11, and this spring exerts its pull to draw the escapement dog 39 into alignment with the latching dog 41 when the writing head 10 is at that end of the carriage 11, which marks the end, or substantially the end, of a line of writing. When the head 10 is at the opposite end of the carriage 11, or that which marks the beginning of a line of writing, the escapement dog 39 occupies the position illustrated in Fig. 4, or out of alignment with the latching dog 41, this being due to the fact that the dog 39 is controlled by an actuator 46 having a flexible connection 47 with the escapement dog 39. The actuator 46 is in the form of an L-shaped slide the horizontal arm of which is provided with a plurality of slots 48 in which screws 49 are seated, and by which screws the actuator 46 has limited sliding movement on the carriage 11. The vertical arm of the actuator 46 extends into the path of a contact finger 49 which is mounted on the writing head 10. The sliding movement of the actuator 46 is of but limited extent, and as the writing head 10 moves toward the end of the line of writing the contact finger 49 moves away from the vertical arm of the actuator 46, thus permitting the spring 45 to swing the escapement dog 39 into alignment with the latching dog 41 when the head 10 has moved a sufficient distance. On the reverse movement of the head 10 however, as when it is moved to that side of the carriage 11 marking the beginning of a line of writing, the contact finger 49 again engages the vertical arm of the actuator 46, inducing movement therein to swing the escapement dog 39 out of alignment with the latching dog 41. This permits the carriage 11 to be moved backwardly and forwardly on the rails 12 without movement of the operating slide 35.

The practical effect of the construction just described is to reciprocate the feed plate 27 relatively to the card magazine when the escapement dog 39 is in alignment with the latching dog 41, and to permit the feed slide to remain at rest when such alignment of said dogs does not occur. Therefore, only when the writing head is in the position which marks the end of a line of writing, rather than the beginning of such line, will engagement of the dogs 39 and 41 arise. This has practical value in that it is such position of the writing head which occurs after the operator has finished the stencilling of the card on the platen 13 and this card is ready to be ejected and replaced by a new card for printing and stencilling. At such time the carriage 11 is moved rearwardly so as to bring the forward member of the carriage into contact with the stop dog 16, as shown in Fig. 1, whereupon the dog 39 engages the latching dog 41 to move the operating slide 35 rearwardly, project the plate 27 into contact with the lowermost card of the stack in the magazine, and move that card towards the front of the machine or in the direction of the platen 13. The writing head 10 is then shifted to the beginning of the line of writing, or to the left as the structure is viewed in Fig. 1, whereupon the contact finger 49 engages the vertical arm of the actuator 46, swinging the escapement dog 39 out of alignment with the latching dog 41, and permitting the spring 36 to retract the feed plate 27 and also move the operating slide 35 forwardly or to the normal position of the latter.

With the position of the writing head 10 at the completion, or substantial completion, of a line of writing, or at the right of the structure as viewed in Fig. 1, the escapement dog 39 is always positioned for engagement with the latching dog 41, and the frame 11 may be moved backwardly and forwardly repeatedly for actuating the slide 35 and the plate 27 in a series of movements for ejecting successive cards from the magazine.

This operation of the parts is followed when a fresh stack of cards is placed in the magazine, or when there is not a sufficient number of cards in the guide channels 26 for successive introduction of the cards to the platen 13 after a card has been stencilled and is removed from the platen. In this movement it will be obvious that when the frame 11 is drawn forwardly the latching dog 41 10 will be depressed by the escapement dog 39, the latter riding over the former, and as soon as the escapement dog has cleared the latching dog 41 this dog is again projected upwardly by the spring 44 for reengagement 15 by the escapement dog 39 on the next rearward movement of the frame 11.

It is desirable that as the card to be printed and stencilled is introduced to the platen 13 the forward movement of the card 20 should be checked so as to position the same on the platen at a proper point to be typed and stencilled. Mechanism is provided for this purpose designed to be actuated by the feed plate 27 in its forward movement for 25 ejecting the lowermost card of the stack from the magazine. The mechanism in question is most clearly illustrated in Figs. 2, 8 and 9. It consists of a plunger rod 50 the rear end of which is slidably mounted in the 30 machine frame in the plane of the feed plate 27. The forward end of the rod 50 has a swivel connection with a bell-crank lever 51 the horizontal arm of which terminates in a handle 52. The bell-crank lever 51 is pivotally mounted in a vertical slot 53 formed in a hanger block 54 arranged at the under face of the platen 13. The slot 53 opens rearwardly and receives the forward end of the plunger rod 50 by means of which that 35 end of the rod is slidably mounted and guided in the hanger block. A stop pin 55 is also arranged in the slot 53, its upper end projecting through an opening in the platen 13, the lower end of the pin having a head 40 56 against which a coil spring 57 rests. The opposite end of the spring 57 abuts against the upper end of the slot 53, so that the compressive action of the spring is utilized to force the bell-crank lever 51 downwardly 45 with a resultant rearward thrust of the plunger rod 50. This positions the rear end of the rod 50 for ready contact by the plate 27 and forward movement of the rod as the plate 27 continues to move forwardly after 50 such contact has been established. On this forward movement of the rod 50 the upper end of the pin 55 is projected above the upper surface of the platen 13 and into the path of the advancing card which is being 55 pushed on to the platen. When the card contacts with the pin 55 the card comes to rest and is positioned over the platen 13 for application of the typing and stencilling at the appropriate points thereon. On the re- 60 traction of the feed plate 27 the spring 57 65

forces the bell-crank lever 51 downwardly and projects the plunger rod 50 rearwardly. This action of the spring also pushes the pin 55 downwardly, and removes the same from the forward path of movement of the card 70 on the platen in the discharge of the card from the platen.

It will be understood that in the space intervening the card on the platen 13 and the magazine a plurality of cards will be in 75 transit from the magazine to the platen through the guide channels 26. To insure the proper presentation of each card to the platen 13 a guiding bar 58 extends between the guide members 23, that edge of the bar 80 58 which is nearest to the magazine being rounded off so as to permit the advancing edge of the card to ride thereover and be deflected upwardly thereby in order to enter upon the platen 13. In the event that any 85 of the cards are slightly distorted, or buckled, the guiding bar 58 acts upon the same to bring the advancing edges thereof into proper alignment with the surface of the platen 13 for entry thereon.

In stencilling the fibrous sheet 22 of the card 21, it has been found desirable to moisten the same in advance of the cutting operation. This practice is usually followed in the stencilling of record cards of this sort. 90 To accomplish such moistening in the present machine is one of the objects of the invention, and in pursuance of that object it is necessary that the application of the moisture shall be properly timed with respect to the movement of the cards from the magazine to the platen 13. In the present embodiment a moistener pad 59 is employed. This comprises a supporting core 60, in the form of an elongated plate, and an absorbent covering 61 therefor. This covering is composed of some suitable material, preferably of a textile character, the same being wrapped around the core 60, and its edges are of sufficient length to provide 100 skirted portions which dip into a water bath 62. This bath is a pan of any suitable character arranged within the machine frame, and preferably located beneath the card magazine. With the skirted portions of the absorbent covering 61 immersed in the water of the bath, the pad itself is fed by capillary attraction, and becomes saturated to the required extent to apply moisture to the stencil sheet 22 of the lowermost card of the stack. The pad 59 is of substantially the same dimensions as that of the stencilled sheet 22, so that the surface of the latter comes into contact with the pad and its moistening is thereby insured.

The pad 59 and its core 60 are carried by a pair of supporting arms 63, the rear ends of the latter being pivotally connected, as at 64, to suitable points at the rear of the machine frame. To each of the arms 63 is

connected a spring 65, these springs being also anchored to the guide members 23 and exerting their force to elevate the moistening pad 59 and maintain the same in contact with the stencil sheet of the lowermost card in the magazine.

Mounted on one of the arms 63 is a contact roller 66, which roller is engaged by a cam finger 67 which is arranged at the lower side 10 of the feed plate 27 so as to be movable therewith. As the feed plate 27 advances the cam finger 67 engages the roller 66, and thereby forces the arms 63 downwardly so as to lower the moistening pad 59 from contact with the stencil sheet of the lowermost card, and also to depress the pad sufficiently to be out of the path of movement of the plate 27 as it advances in the discharge of the lowermost card from the stack. It will 20 thus be apparent that in the operation of the machine the period of contact of the moistening pad with the stencil sheet of each card is only of the duration of the presence of the card which is being acted on at the platen 13. But this period is sufficient for the required moistening of the stencil sheet.

For the convenient supplying of water to the pan 62 and at the same time to permit the arms 63 readily to be depressed in the 30 operation of the pad 59 to and from the stack of cards, the pan 62 is provided with a notched portion 68. This receives one of the arms 63 in the movement of the latter, and permits one end of the pan 62 35 to extend beyond the adjacent guide member 23, so that water may be readily introduced to the pan without removing the same from the machine frame.

In the return of the feed plate 27 by the 40 contraction of the spring 36 to the rearmost position of the plate, it is necessary to limit the rearward movement of the latter, and at the same time to cushion the plate against shock when the same is brought to rest in reaching that limit. To this end a buffer block 69 is arranged at the rear of the machine frame, the same being held in 45 position by a clamping plate 70 mounted upon attaching screws 71 applied to the machine frame. The buffer block is formed 50 of any suitable material, such as a proper fibrous substance, rubber or the like. A fibrous substance, however, is preferred because of its greater durability. The buffer 55 block 69 projects upwardly so as to be contacted by the rear edge of the plate 27, and in this position the rearward movement of the plate 27 is limited, as indicated.

From the foregoing description the operation 60 of the herein-described feed mechanism is apparent and briefly described as follows:

Assuming none of the record cards to be 65 in the guide channels 26, and the magazine also to be free of the cards, a stack

of the latter is placed in the magazine. They gravitate to the lowermost point, and the bottommost card rests upon the guide members 23 and in the plane of the engaging dog 29. The writing head 10 is now 70 moved to the right of the structure as viewed in Fig. 1, so that the escapement dog 39 becomes positioned for engagement with the latching dog 41. The frame 11 is now 75 moved back and forth several times, the dogs 39 and 41 becoming engaged and disengaged in the manner previously described, and thereby actuating the feed plate 27 to feed cards from the magazine into the guide channels 26 to the necessary extent to position 80 one of the cards on the platen 13. The writing head 10 is now moved to the left of the structure shown in Fig. 1, which positions the head in proper relation to the card on the platen to permit the same to 85 be typed and stencilled. After this has been completed, and while the writing head 10 remains in proper relation to engage the escapement dog 39 with the latching dog 41, the frame or carriage 11 is moved rearwardly, thereby moving the operating slide 90 35 rearwardly and projecting the feed plate 27 forwardly. With the train of cards now present in the guide channels 26, and intervening the space between the platen 13 95 and the magazine, the completed card on the platen is forced forwardly and discharged from the platen, while the next succeeding card is presented to the platen for typing and stencilling. This, of course, follows because on the advance of the feed plate 27 100 the lowermost card of the stack is projected forwardly by that plate.

During the typing and stencilling of the card on the platen 13, the moistener pad 105 59 is in engagement with the lowermost card of the stack, thereby moistening the stencil sheet of that card, and on the next advancing movement of the feed plate 27, the cam finger 67 acts on the roller 66 to 110 depress the pad 59, and thereby free the lowermost card for movement away from the magazine. It is to be noted in this connection that the application of the moistener pad is to the stencil sheet of the card 115 only. The pad contacts no other surface of the card, so that the card remains dry in other respects. This is a decided advantage in that there is no moistened surface to be 120 typed with a consequent blurring of the surface due to moisture.

Concurrently with the advancing of the feed plate 27 to card-discharging position 125 in relation to the magazine, the forward edge of the plate 27 also engages the push rod 50 to advance the latter and, through the medium of the bell-crank lever 51, project the stop pin 55 upwardly and into the path of forward movement of the card which is being introduced to the platen 13. 130

The pin 55 remains in this projected condition until the card has been properly placed on the platen 13, and only on retraction of the plate 27 does the spring 57 reassert it 5 self to withdraw the pin 55 from its projected condition.

Thus it will be seen that the herein-described invention provides feed mechanism of relatively simple character for incorporation with stencil cutting attachments, and particularly attachments of this nature applied to book or flat platen typewriting machines. When so incorporated and combined the output of the machine is greatly increased, and the energy of the operator obviously conserved. This is due to the fact that in the feed of the cards from the magazine to the platen 13 there is utilized only those movements of the operator which must necessarily be made in the operation of the writing head 10 when typing and stencilling the cards, and the actuation of the feed mechanism is effected as an incident to the operation of the typewriting machine in the typing and stencilling movements.

The preceding description contemplates record cards as the particular material used in connection with the improvements herein illustrated and described. It will be understood, of course, that any material in the form of sheets may be employed, so that the feed mechanism constituting the present improvement is applicable to any form of sheet material utilized under circumstances such as has been outlined with respect to the record cards.

I claim:

1. In mechanism of the class described, the combination with a writing head, and a platen operatively related thereto, of a magazine for the cards or sheets to be acted on by the writing head, and means operable by the writing head for feeding said cards or sheets from the magazine to said platen, said feeding means being responsive to the movements of the writing head when positioning the latter with respect to the platen to establish operative relation between the writing head and said feeding means, and means for interrupting the operative relation between the writing head and the feeding means when the writing head is moved in the direction of a line of writing.

2. In a machine of the class described, the combination with a writing head, and a platen operatively related thereto, of a magazine for the cards or sheets to be acted on by the writing head, means for feeding said cards or sheets from the magazine to said platen, means for intermittently applying moisture to the cards or sheets, and connections operable by the writing head in the relative movements of the latter with respect to the platen for utilizing such movements 65 of the writing head to effect operation of

said feeding means and said moisture-apply-ing means.

3. In a machine of the class described, the combination with a writing head, and a platen operatively related thereto, of a mag- 70 azine for the cards or sheets to be acted on by the writing head, means for applying moisture to the cards or sheets at an intermediate point between the platen and the magazine, means for intermittently actuat-ing said moisture-applying means, and connec-tions operable by the writing head in the relative movements of the latter with respect to the platen for utilizing such movements of the writing head to effect operation 80 of said moisture-applying means.

4. In a machine of the class described, the combination with a writing head, and a platen operatively related thereto, of a mag- 85 azine for the cards or sheets to be acted on by the writing head, means for applying moisture to the cards or sheets, means for moving said moisture applying means to-wards and away from the cards or sheets at predetermined times in the feed of the 90 cards or sheets from the magazine to the platen, and connections operable by the writing head in the relative movements of the latter with respect to the platen for utilizing such movements of the writing head to effect 95 operation of said moisture-applying means.

5. In a machine of the class described, the combination with a writing head, and a platen operatively related thereto, of a mag- 100 azine for the cards or sheets to be acted on by the writing head, a moisture bath, means interposed between said moisture bath and the cards or sheets for applying moisture to the cards or sheets, means for moving the moisture-applying means into contact relation with the successive cards or sheets as the latter pass from the magazine, and connec-tions operable by the writing head in the relative movements of the latter with respect to the platen for utilizing such movements 110 of the writing head to effect operation of said moisture-applying means.

6. In a machine of the class described, the combination with a writing head, and a platen operatively related thereto, of a mag- 115 azine for the cards or sheets to be acted on by the writing head, a moisture bath, a move-able pad located beneath the magazine and interposed between the moisture bath and the cards or sheets, means for effecting relative operation between said movable pad and the cards or sheets to apply moisture to the successive cards or sheets in the magazine, and connections operable by the writing head in the relative movements of the latter 120 with respect to the platen for utilizing such movements of the writing head to effect 125 operation of said movable pad.

7. In a machine of the class described, the combination with a writing head, and 130

- 5 a platen operatively related thereto, of a magazine for the cards or sheets to be acted on by the writing head, means actuated by the writing head for feeding the cards or sheets from the magazine to said platen, and means controlled by said feeding means for moistening the cards or sheets and operable in timed relation to the movement of the feeding means for feeding the cards or sheets.
- 10 8. In a machine of the class described, the combination with a writing head, and a platen operatively related thereto, of a magazine for the cards or sheets to be acted on by the writing head, means actuated by the writing head for feeding the cards or sheets from the magazine to said platen, means for moistening the cards or sheets while the feeding means are at rest, means for removing the moistening means from the cards or sheets when the feeding means are operated to transfer the cards or sheets from the magazine to the platen, and connections operable by the writing head in the relative movements of the latter with respect to the platen for utilizing such movements of the writing head to effect operation of said card-feeding means and moistening means.
- 15 9. In a machine of the class described, the combination with a writing head, and a platen operatively related thereto, of a magazine for the cards or sheets to be acted on by the writing head, means actuated by the writing head for feeding the cards or sheets from the magazine to said platen, means located beneath the magazine for moistening the successive cards or sheets while the feeding means are at rest, operative connections between the feeding means and the moisture-applying means for removing the latter from contact relation with the cards or sheets when the feeding means are brought into operation, and connections operable by the writing head in the relative movements of the latter with respect to the platen for utilizing such movements of the writing head to effect operation of said card-feeding means and said moisture-applying means.
- 20 10. In a machine of the class described, the combination with a writing head, and a platen operatively related thereto, of a magazine for the cards or sheets to be acted on by the writing head, means for feeding said cards or sheets from the magazine to said platen, and card-positioning means associated with the platen, and operable by the feeding means to position the cards or sheets on the platen when the feeding means are actuated.
- 25 11. In a machine of the class described, the combination with a writing head, and a platen operatively related thereto, of a magazine for the cards or sheets to be acted on by the writing head, means for feeding said cards or sheets from the magazine to said platen, card-positioning means associated with the platen, and means for actuating said card-positioning means in timed relation to the actuation of the card-feeding means to bring a card or sheet to rest on the platen in appropriate relation for action thereon by the writing head.
- 30 12. In a machine of the class described, the combination with a writing head, and a platen operatively related thereto, of a magazine for the cards or sheets to be acted on by the writing head, means for feeding said cards or sheets from the magazine to said platen, card-positioning means associated with the platen, and connections between said feeding means and said positioning means for conditioning the latter for action on the cards or sheets in timed relation to the advance of the cards or sheets to the platen under the influence of said feeding means.
- 35 13. In a machine of the class described, the combination with a writing head, and a platen operatively related thereto, of a magazine for the cards or sheets to be acted on by the writing head, means for feeding said cards or sheets from the magazine to said platen, an escapement between the writing head and the feeding means for operatively relating the writing head to said feeding means in one direction of movement of the writing head, and means whereby the operative relation of the writing head to the feeding means is broken in an opposite direction of movement of the writing head.
- 40 14. In a machine of the class described, the combination with a writing head, and a platen operatively related thereto, of a magazine for the cards or sheets to be acted on by the writing head, means for feeding said cards or sheets from the magazine to said platen, an escapement between the writing head and the feeding means for operatively relating the writing head to said feeding means in one direction of movement of the writing head, means whereby the operative relation of the writing head to the feeding means is broken in an opposite direction of movement of the writing head, and means for applying moisture to the cards or sheets in their transit from the magazine to the platen.
- 45 15. In a machine of the class described, the combination with a platen, of a writing head arranged over the same, a magazine for the cards or sheets to be acted on by the writing head, a reciprocating feed device operative with respect to said magazine to feed the cards or sheets from the magazine to the platen, moisture-applying means for moistening the cards or sheets while the latter remain in the magazine, and means for removing the moistening means from moisture-applying relation to the cards or sheets.

to permit discharge of the latter by said feed device.

16. In a machine of the class described, the combination with a platen, of a writing head arranged over the same, a magazine for the cards or sheets to be acted on by the writing head, reciprocating moisture-applying means for moistening the cards or sheets while the latter remain in the magazine, a reciprocating feed device operative with respect to said magazine to feed the cards or sheets from the magazine to the platen, and means associated with the feed device and actuated thereby for removing the moistening-means from moisture-applying relation to the cards or sheets to permit discharge of the latter by said feed device from said magazine.

17. In a machine of the class described, the combination with a platen, of a writing head arranged over the same, a magazine for the cards or sheets to be acted on by the writing head, a reciprocating feed device operative with respect to said magazine to feed the cards or sheets from the magazine to the platen, moisture-applying means for moistening the cards or sheets while the latter remain in the magazine, means for removing the moistening-means from moisture-applying relations to the cards or sheets to permit discharge of the latter by said feed device and connections operable by the writing head in the relative movements of the latter with respect to the platen for utilizing such movements of the writing head to effect operation of said reciprocating feed device and said moisture-applying means.

18. In a machine of the class described, the combination with a platen, of a writing head arranged over the same, a magazine for the cards or sheets to be acted on by the writing head, reciprocating moisture-applying means for moistening the cards or sheets while the latter remain in the magazine, a reciprocating feed device operative with respect to said magazine to feed the cards or sheets from the magazine to the platen, means associated with the feed device and actuated thereby for removing the moistening-means from moisture-applying relation to the cards or sheets to permit discharge of the latter by said feed device from said magazine, and connections operable by the writing head in the relative movements of the latter with respect to the platen for uti-

lizing such movements of the writing head to effect operation of said reciprocating feed device and said moisture-applying means.

19. In a machine of the class described, the combination with a platen, and a writing head arranged above the same and mounted for line and letter spacing movements relatively to the platen, of a magazine for the cards or sheets to be acted on by the writing head, means for feeding the cards or sheets from the magazine to said platen in the line-spacing movement of the writing head, and connections between the writing head and the feeding means controlled by predetermined positions of the writing head in the letter-spacing movement thereof for controlling movement of said feeding means.

20. In a machine of the class described, the combination with a platen, and a writing head arranged above the same and mounted for line and letter spacing movements relatively to the platen, of a magazine for the cards or sheets to be acted on by the writing head, means for feeding the cards or sheets from the magazine to said platen in the line-spacing movement of the writing head, means for moistening the cards or sheets before the latter are presented to the platen, the moistening action of said means being controlled by said feeding means, and connections between the writing head and the feeding means controlled by predetermined positions of the writing head in the letter-spacing movement thereof for controlling movement of said feeding means.

21. In a machine of the class described, the combination with a writing head, and a platen operatively related thereto, of a magazine for the cards or sheets to be acted on by the writing head, means located beneath the magazine for applying moisture to the cards or sheets, means for moving said moisture-applying means towards and away from the lowermost card or sheet in the magazine at predetermined times in the feed of the cards or sheets from the magazine to the platen, and connections operable by the writing head in the relative movements of the latter with respect to the platen for utilizing such movements of the writing head to effect operation of said moisture-applying means.

In testimony whereof I have hereunto signed my name.

NATHAN C. HEATON.
